ABSTRACT: The invention concerns an alarm system for detecting abnormal or emergency conditions and reporting them in response to placement of a call to an associated telephone. The system comprises a circuit including two switch means one operable by a detector in response to an abnormal condition, and the other operable in response to a call placed to the telephone, so that no alarm signal is generated until a call is received. The system need not be incorporated into the telephone circuit, but can be a self-contained unit that transmits an alarm signal via the telephone.

TELEPHONE ALARM SYSTEM

BRIEF DESCRIPTION OF THE INVENTION

It is the general object of this invention to provide an improved alarm system for detecting any abnormal or emergency condition at a remote location by telephone. More specific objects are to provide an improved alarm system which is self-contained and does not require incorporation into the telephone system, which can be installed or moved easily without technical knowledge, which is adapted to report any physical condition which can be detected, which is compact and inexpensive, which does not interfere with the normal use of the telephone, and which has a long service life with a minimum maintenance requirement. Other objects and advantages of the invention will appear as the following description proceeds.

The improved alarm system is especially adapted for use by homeowners, for the purpose of checking on the security and safety of the home when the owner is absent. Various utilities can be checked, such as the maintenance of electrical power, heat, water and fuel supplies. Dangerous conditions, including flooding, freezing of water pipes, extinction of pilot lights in stoves and heaters, excess accumulations of snow, and appliances inadvertently left in operation, can also be detected. The owner has only to place a call to his home telephone; if everything is in good order, there will be no response, but the existence of an abnormal condition produces a distinctive signal on the telephone.

Another important use of the system is for checking by oil companies of the fuel levels in their customers' tanks. The conventional practice has been to estimate oil usage on the basis of prevailing temperatures; this affords only a rough approximation, and often leads to unnecessarily frequent delivery calls, or more importantly, to exhaustion of the customer's tanks. The improved system can incorporate a tank level detector, so that an oil company can determine whether deliveries are needed simply by calling its customers' telephones.

A preferred embodiment of the invention includes a circuit having two switch means, one of which is operable by one or more detectors or transducers arranged to monitor whatever physical conditions the user may select. The second switching means is operated by a transducer responsive to placement of a call to the telephone with which the alarm system is associated; this transducer may be a contact microphone or a sound microphone responsive to the ringing of the telephone, or an inductive pickup responsive to the current flow in the telephone cable. Thus, the circuit is energized only when both switching means are operated; an alarm signal is not initiated by the occurrence of an abnormal condition until a call is placed. This conserves power, and permits the use of ordinary flashlight batteries for a power supply, which are readily available even in remote locations. The system does not require household current, which is subject to failure under emergency conditions.

The circuit also includes means for producing a signal to the caller. These means preferably comprise a motive means for raising the telephone receiver from its cradle, and a speaker for generating a distinctive sound signal audible over the telephone. Raising the telephone from its cradle without an audible signal will also signal the caller that the circuit has been activated, because the ringing will stop and the telephone circuit will be completed. The motive means may comprise a servomotor or solenoid, together with a pivoted lever which is placed on the telephone cradle and extends between its arms under the receiver. The lever is pivotable by the motive means to raise the receiver from its cradle, and then to lower it after the alarm signal has been delivered. A servomotor may drive the lever through a speed-reduction drive and an escapement which moves the lever in intermittent steps. The escapement introduces a time delay in the answering of a call so that the caller can more readily identify the alarm signal, and determines the length of the signal.

It is also possible to simulate the lifting of the receiver from the cradle electrically by incorporating a connection to the telephone wires and a suitable switch.

The operation of the alarm system is terminated by a third

5 switch means after a signal has been delivered. These means may be a commutator switch driven by the motive means to deenergize the system after a cycle of mechanical operation, or a time-delay relay. The latter is preferred if a sound-responsive microphone is used, to prevent recycling of the system by 10 feedback of its own alarm signal. A contact microphone will not respond to an alarm signal delivered by a loudspeaker, so that there is no requirement to overcome recycling if this combination of transducer and signalling device are used.

It may be desired to delay the operation of the system after a 15 call is initiated, to permit the homeowner to answer calls when at home without possible interruption by the alarm system, so that it is not necessary to remove the system from the telephone for normal use. Such a delay would also allow other subscribers on a party line ample time to answer their calls 20 without interference from the alarm system. This function can be performed by a time-delay relay included in the circuit, or by a mechanical device such as a dashpot or the escapement previously described.

25 DETAILED DESCRIPTION OF THE DRAWINGS AND PREFERRED EMBODIMENTS

While the specification concludes with claims particularly pointing out the subject matter which we regard as our invention, it is believed that a clearer understanding may be gained 30 from the following description of preferred embodiments thereof, referring to the accompanying drawings, in which:

FIG. 1 is a perspective view showing one form of the invention in operative association with a conventional telephone;

FIG. 2 is a sectional view in side elevation;

FIG. 3 is a fragmentary sectional plan view of mechanical elements of the alarm system;

FIG. 4 is a sectional view taken along line 4-4 in FIG. 3, looking in the direction of the arrows;

FIG. 5 is a sectional view taken along line 5-5 in FIG. 3, looking in the direction of the arrows;

FIG. 6 is a circuit diagram of a form of the system usable with a contact microphone, shown with several illustrative types of condition detectors; and

FIG. 7 is a circuit diagram of another form of the system usable with a sound microphone, and including means for delaying response of the system after a call is placed.

Referring first to FIGS. 1-3, the alarm system is compactly mounted in a housing 10 placed to the rear of a conventional telephone T. A cover 12 is attached to the housing by screws 14, and carries a mounting bracket 24 which extends substantially horizontally between the arms 28 of the telephone cradle. The bracket is attached at its forward end to a hinge 22, which extends laterally beyond the arms 28 into ears 26 for supporting the housing 10 removably on the telephone cradle. A lever 18 is pivotally mounted by the hinge, extending rearwardly under the telephone receiver 30 to the housing. The lever 18 terminates in a hook portion 20, extending freely through a slot 16 in the cover 12 into the interior of the housing. The receiver may be raised from its cradle to a position 30' high enough to complete a telephone circuit, by raising the lever to position 18' (FIG. 2), and lowered back onto the cradle by a reverse movement of the lever. The raised position 18' is high enough to complete the telephone circuit, but the receiver is not raised above the forward arms 28 so that it could become displaced from alignment with the cradle.

The housing 10 also mounts a test pushbutton 32, and a connector means or receptacle 36 for a cable 38 extending to one or more condition detectors or transducers which will be 70 described further hereinafter, but are illustrated by a temperature sensor bulb TS. A contact microphone CM is attached to the telephone by a clip (not shown), and is connected to the system by a cable 42. A series of holes 34 are formed in the cover plate 12, and a speaker S (not shown in FIGS. 1-3) is mounted on the reverse face of the plate behind these holes.

Referring now more particularly to FIGS. 2-5, a motor M is mounted within the housing on brackets 46 attached to a baseplate 70. The motor drives a speed-reducing gear train including a worm 48, worm gear 50 and pinion 52 fixed on a common shaft 51, and a gear 54 fixed on a shaft 60. A crank 55 having two axially extending pins 56 is mounted on the shaft 60, and cooperates with the arms of a star wheel 58 fixed on a shaft 62, to form an escapement or intermittent lost-motion drive. The star wheel is turned in intermittent steps in the direction shown by the arrows in FIG. 4.

Retrograde motion of the star wheel 58 is prevented by a lever 64, forming a pawl 65 biased toward engagement with the star wheel by a tension spring 66. The lever is pivoted on one of several posts 63 which mount a cover plate 68 on the baseplate 70. As the star wheel is turned by engagement with one of the pins 56, the lever 64 is deflected to allow the oncoming arm of the star wheel to pass; subsequent release of the star wheel by the driving pin 56 is accompanied by latching of the star wheel by the pawl 65.

The star wheel 58 and shaft 62 drive a commutator disc C, and a cam means comprising a crank 67 carrying a drive pin 72. The hook portion 20 of the lever 18 rests on the pin 72, so that a half-revolution of the crank 67 raises the lever to the position 18' (FIG. 2) to lift the receiver 30 from its cradle, and the completion of a full revolution lowers it to hang up the receiver.

The commutator C has a conductive surface which is interrupted over an arcuate sector by an insulating portion 74. The conductive portion is electrically connected by the drive train to a ground lead of the motor M. A conductive brush 76 rests in frictional sliding engagement against the face of the commutator disc, and is mounted by an insulating support 78 on a platform 75 attached to the plate 68. The commutator provides a switch means for interrupting operation of the motor M after a single revolution of the shaft 62 and the crank 67, during which one cycle of raising the receiver 30 and returning it to its cradle is carried out.

The housing 10 accommodates a casing 79 (see FIG. 2) mounting batteries B for energizing the system; it also encloses a loudspeaker S and a switching circuit AS, which are shown in the circuit diagram of FIG. 6.

The alarm system may be connected to any desired number of condition detectors, each including switch means which remain open while the detected condition remains within normal limits, but which are closed by a transducer in response to an abnormal deviation. By way of illustration, three detectors are shown. These include a temperature-responsive switch TS incorporating a thermostatic bimetallic element or expansion bulb; a power relay contact 1PR which is held open by a power relay PR connected across power supply lines unless a power failure occurs, permitting the contact to close; and a fuel supply switch FS which is closed by a float 86 in a fuel tank 84 in the event that the fuel level 88 decreases below a predetermined height.

The switches TS, 1PR and FS are connected in parallel, and are connected as a group by the cable 38 and the connector means or receptacle 36 in series relation to the remainder of the circuit. A junction box 80 is schematically illustrated as a convenient means for connecting the various detectors. Pilot lamps (not shown) for each detector may be incorporated in this box as a ready means for identifying which of the various detectors has located an abnormal condition, after an alarm signal has been delivered.

The batteries B are connected through the connector receptacle 36 in series with the loudspeaker S and the motor M. The test pushbutton 32 is connected in parallel with the receptacle 36 so that the operation of the system and the condition of the batteries can be checked when the detected conditions are normal. A resistor R1 shunts a portion of the available power from the speaker to the motor. The motor circuit is completed alternatively through the commutator C and its brush 76, or through a silicon-controlled transistor rectifier SCR, which is incorporated in a microphone-amplifier circuit AS.

The contact microphone CM attached to the telephone T responds to the ring of the telephone bell, and its impulses are amplified by a transistor amplifier A. The rectifier SCR and amplifier A are coupled in a conventional manner by resistors R2, R3, R4, and R5, and a capacitor C1, in such a manner that the amplified calling signal switches the rectifier to a conductive state.

In the event that any one of the detector switches TS, 1PR, or FS is closed when a call is placed to the telephone, a circuit 10 through the motor M and speaker S is completed through the rectifier SCR. The circuit remains incomplete, even though one of the detector switches is closed, until the receipt of a call renders the rectifier conductive.

As the motor is initially energized, the commutator switch C is rotationally positioned as shown, with the brush 76 engaging the insulated portion 74; but as the motor rotates the commutator, the brush engages the conductive surface. The resulting closing of the commutator switch bypasses the motor circuit through the commutator to the batteries, and short circuits the amplifier circuit AS, thereby causing the rectifier SCR to assume a nonconductive state. The motor continues to operate until the commutator has rotated one full revolution, and the brush 76 once again encounters the insulated portion. This breaks the motor speaker circuit and shuts the device off, ready for the next cycle of operation.

As the motor turns the commutator and the crank 67 through one revolution, the telephone receiver is lifted to complete the telephone circuit, while the loudspeaker is energized 30 to produce an audible signal generated by the electrical noise of the motor. This signal is clearly audible to the calling person. The receiver is then returned to its cradle as the commutator C shuts off the system.

The delay in completing the telephone circuit which is occasioned 35 by the escapement or lost-motion drive previously described, results in a characteristic time sequence of response which is easily recognized by the caller. We prefer to arrange the mechanical drive to hold the receiver off its cradle for about 3 to 5 seconds, long enough to enable the caller to 40 clearly recognize the alarm signal. In use with telephones in party line systems, an increased delay in lifting the receiver can be incorporated into the mechanical drive, or by adding a time-delay relay, of sufficient duration to enable all parties to receive their calls without interference from the alarm system.

While the conditions detected by the switches TS, 1PR, and FS remain normal, there is no current flow from the batteries B. Ringing of the telephone draws no current because the amplifier switch AS is disconnected. When any of the detector 50 switches are closed by an abnormal condition, a minute current flows through the amplifier switch, but this is too small to affect the power of the batteries unless it persists for a long period of time. Substantial power is drained from the batteries only during the short interval when an alarm signal is being delivered to a caller, so that a long battery service life is obtained.

A microphone CM of the contact type, used in combination with a loudspeaker S, is preferred because it averts recycling of the system in response to the feedback of its own alarm signal. A buzzer signal might produce a recycling feedback response even in a contact microphone. But a sound microphone can be used in combination with a speaker or buzzer, or a contact microphone can be used with a buzzer, if an appropriate time-delay relay is added to the system to discontinue its operation after a predetermined interval.

A system is shown in FIG. 7 which incorporates a sound-sensitive microphone and time-delay means for preventing recycling by an alarm signal generated by the system. A single normally open condition detector switch TS is shown by way 70 of illustration, connected in series with the battery B by the connector receptacle 36. A normally closed contact 1TR2 of a time-delay relay TR2 connects the battery in series with a normally open microphone-amplifier switch AS, which is operable by a sound microphone SM in response to the ring of the telephone T.

In the event that an abnormal condition closes the switch TS, and a call is placed to the telephone, the resulting closure of the switch AS energizes a locking relay LR. This relay closes a normally open relay contact 1LR, energizing time-delay relays TR1 and TR2. The relay TR1 closes its normally open contact 1TR1 only after a predetermined interval, which serves to delay the operation of the alarm system. Closure of the contact 1TR1 energizes a speaker S and a solenoid RS, which is mechanically connected to raise the receiver of the telephone T and thus complete the telephone circuit to deliver the alarm signal to the caller.

The relay TR2 times for a period which is longer than that of the relay TR1 by an interval which determines the length of operation of the alarm system. At the end of this period, this relay opens its normally closed contact 1TR2 and deenergizes the system, causing the solenoid RS to return the telephone receiver to its cradle. The feedback of the alarm signal to the microphone SM does not cause the system to recycle because the amplifier switch AS is disconnected. Deenergization of the locking relay LR by the contact 1TR2 prepares the system for an ensuing cycle, instituted by another call to the telephone, by deenergizing the relays TR1 and TR2.

It should be noted that the time-delay relays TR1 and TR2 may be incorporated into the circuit of FIG. 6 if desired, the former to introduce a fixed delay in responding to a call to the associated telephone, and the latter to prevent recycling when used with a sound microphone or the combination of a contact microphone and a buzzer.

What I claim is:

1. An alarm system for use with a telephone, comprising circuit means including first and second switch means, said first switch means including a first transducer responsive to an abnormal physical condition to activate said first switch means, said second switch means including a second transducer operable in response to a call to the telephone to activate said second switch means, said circuit means further including means constructed and arranged for producing a signal through the telephone system, said first and second switch means connecting said circuit means to actuate said signal-producing means only when both of said switch means are concurrently in an activated state, whereby said alarm system remains inactive during the existence of an abnormal physical condition until a call is placed to the telephone, and remains inactive during the placing of a call to the telephone unless an abnormal physical condition exists.

2. An alarm system as recited in claim 1, said signal-producing means comprising motive means connected for activation only by closure of both of said switch means, and being constructed and arranged for raising the telephone receiver from its cradle in response to placement of a call to the telephone, and for lowering the telephone receiver to its cradle after an interval to terminate the call.

3. An alarm system as recited in claim 2, said motive means including cam means driven thereby, and a pivoted lever constructed and arranged for raising and lowering a telephone receiver when pivotally oscillated, said cam means engaging said lever to raise and lower the telephone receiver in response to a predetermined cycle of motion of said motive means.

4. An alarm system as recited in claim 3, said motive means further including lost-motion means drivingly connecting said motive means with said cam means and constructed and arranged to raise and lower said lever in intermittent steps and to maintain the position of the lever during intervals between the steps of its movement.

5. An alarm system as recited in claim 2, including bracket means adapted to extend between the cradle and receiver of an associated telephone and having laterally extending ears for retaining said bracket means in place on the cradle, said

motive means including a lever pivoted on said bracket means and constructed and arranged for raising and lowering the receiver when pivotally oscillated.

6. An alarm system as recited in claim 2, said circuit means including a third normally closed switch means operable by said motive means and constructed and arranged to be opened by a predetermined motion of said motive means corresponding to a cycle of raising and lowering of the telephone receiver, thereby to deenergize said circuit means.

7. An alarm system as recited in claim 6, said second switch means being constructed and arranged to close in response to operation of said second transducer by placement of a call to the telephone, and to reopen when short circuited;

10 15 20 25 30 35 40 45 50 55 60 65 70

said third switch means comprising a commutator and brush connected in parallel with said second switch means, said commutator and brush being arranged to form electrical contact during operation of said motive means and subsequent to closure of said first and second switch means, thereby to short circuit and reopen said second switch means while maintaining said circuit means energized, said commutator and brush being arranged to be opened by completion of said predetermined motion to deenergize said circuit means and deactivate said motive means.

8. An alarm system as recited in claim 1, said second transducer comprising a contact microphone sensitive to vibration and insensitive to sound transmitted through the atmosphere, said transducer being adapted for attachment to the telephone for response to ringing of its bell.

9. An alarm system as recited in claim 1, said circuit means including a timed third switch means constructed and arranged to open said circuit means after a predetermined interval of activation of said signal-producing means initiated by placing a call to the telephone, whereby recycling of the alarm system is not instigated by operation of said signal-producing means.

10. An alarm system as recited in claim 9, said second transducer comprising a sound-sensitive microphone.

11. An alarm system as recited in claim 1, said circuit means including a time-delay switch means constructed and arranged to close said circuit means only after a predetermined interval following placement of a call to the telephone, whereby operation of said signal-producing means is delayed and follows the placement of a call to the telephone by said interval.

12. An alarm system as recited in claim 1, said first and second switch means being connected in series in said circuit means and being normally open, activation of said switch means closing said circuit means to actuate said signal-producing means.

13. An alarm system as recited in claim 1, said signal-producing means including sound-producing means for delivering an audible signal through the telephone.

14. An alarm system for use with a telephone, comprising circuit means including connector means adapted for connection by first switch means having a first transducer responsive to an abnormal physical condition to activate said first switch means, said circuit means including second switch means adapted for activation by a second transducer in response to a call to the associated telephone, said circuit means further including means constructed and arranged for producing a signal through the telephone system, said first and second switch means connecting said circuit means to actuate said signal-producing means only when said connector means is connected in said circuit means by activation of said first switch means and said second switch means is concurrently activated, whereby said alarm system remains inactive during the existence of an abnormal physical condition until a call is placed to the telephone, and remains inactive during the placement of a call to the telephone unless an abnormal physical condition exists.
